UNITED STATES PATENT OFFICE.

WILLIAM H. H. HINDS, OF GROTON, MASSACHUSETTS.

IMPROVEMENT IN LANTERNS.

Specification forming part of Letters Patent No. 42,658, dated May 10, 1864.

To all whom it may concern:

Be it known that I, WILLIAM H. H. HINDS, of Groton, in the county of Middlesex, in the State of Massachusetts, have invented a new and Improved Mode of Using Candles in Hand-Lanterns; and I do hereby declare the following to be a full and exact description thereof, reference being had to the accompanying drawing, and to the letters of reference marked thereon, the drawing representing a vertical central section through my improved lantern.

The nature of my invention consists in raising the candle, as it burns away, to the requisite height by means of a spring or otherwise, together with an awl and sleeve, as herein-after described, for the purpose of adjusting it to any desirable position.

To enable others skilled in the art to make and use my invention, I will proceed to describe its construction and operation.

A represents the ordinary hand-lantern; B, a tube, made of tin or other metal, supporting or inclosing spiral spring f, and enter-

ing the bottom of lantern a suitable distance. As the candle D burns away, the expansion of the spring pressing against its bottom will elevate uniformly the light to its original height. E is a sleeve, into which the tube B is inserted when the lamp is designed to have a permanent position. This sleeve is firmly attached to the awl or standard P, which is sharpened at the extremity, that it may more easily penetrate the material when the lamp is required to be used.

What I claim as new, and desire to secure by Letters Patent, is—

1. The application to hand-lanterns of a tube, B, to support the candle D, and the spring f, inclosed within the tube, for the purposes herein described.

2. The standard P and sleeve E, for the support of the lantern, as above set forth.

WM. H. H. HINDS.
